MEANS TO PREVENT BREAKING OF
AWNING VALANCES

William J. Mueller, Racine, Wis.

Application June 12, 1947, Serial No. 754,209

16 Claims. (Cl. 160—56)

1

This invention relates to awnings and especially to the type of awnings having a downwardly hanging valance forming the front portion thereof.

An object of this invention is to provide a means of preventing the valance from blowing up over the roof of the awning. The ultimate effect of this movement of the valance is to tear or break it, necessitating the removal of the entire awning for repairs because the roof and valance are usually stitched together.

Further objects and advantages of this invention will become apparent from a consideration of the following detailed description taken in connection with the accompanying drawings wherein a satisfactory embodiment of the invention is shown. However, it is to be understood that the invention is not limited to the details disclosed but includes all such variations as fall within the spirit of the invention.

Referring to the drawings,

Fig. 1 shows a broken end view of an awning embracing this invention:

Fig. 2 is a fragmentary front view:

Fig. 3 is an enlarged fragmentary end view of the invention:

Fig. 4 is an enlarged fragmentary front view:

Fig. 5 is a sectional view taken at 5—5 of Fig. 4;

Figs. 6 and 7 show sectional and front views respectively of a modification of the detail of Fig. 5, and

Fig. 8 shows the invention applied to an awning having a tubular frame bar.

Described generally, this invention comprises a fabric roof portion R of the awning, a fabric valance V, a hinged member H, a frame F, a connecting means C and a structure S.

Describing the invention specifically, the structure S comprises the support for the awning and is usually a building wall in which are windows or doors over which the awning hangs and to which it is intended to offer protection from the weather.

The frame F comprises a longitudinal front bar 10 which extends the full length of the awning roof R. Bar 10 may be made of wood or other suitable material such as metal tubing or pipe. In this instance the bar 10 is rectangular and is supported a suitable distance from the structure S and parallel thereto by a plurality of support members 11, the latter being usually made of tubing or pipe. One support member being disposed at each end of the awning in this instance. Bar 10 is suitably fastened to the extremity of the support member 11. The ends of support members 11 adjacent the structure S are pivoted to brackets 12, the latter being secured to the structure S by suitable fastening means.

The roof R in this instance, is mounted upon

1
2
a drum D which extends the length of the roof R and upon which the roof is rolled when not in use. The drum D is journaled in suitable brackets fastened to the structure S. The means for rolling the awning up when not in use will not be described, as this arrangement is conventional and not a part of this invention.

When the awning is in the downward or unrolled position, the support members 11 are in the horizontal position as shown in Fig. 1. The lower surface of the bar 10 is also horizontal when the awning is in use.

Secured to the roof R by stitching or other suitable means is the downwardly-extending valance V which hangs a substantial distance below the bar 10. The purpose of the valance V is partly for ornamentation and also to provide space for firm names and addresses. The valance is customarily made of fabric similarly to that used for the roof R. It is usually made independently of the roof R and then stitched thereto. The reason for doing this is to enable the valance V to be easily handled when stenciling lettering thereto. Heretofore an independent valance has been usually considered necessary because of the damage done by wind, necessitating the replacement of the valance. This invention will largely make the removal of the valance unnecessary because the valance will not be able to blow up over the roof of the awning. The invention is especially valuable in windy localities, where without this invention costly repairs may be frequent.

The dotted lines of Fig. 1 show the awning partially raised and shows the position of the valance and the hinged member H as assumed at an intermediate position. It is clear that, as will be later explained, this invention will effectively prevent the damage to the valance caused by wind.

Hinge means H and connecting member C comprises the gist of the invention taken in combination with the awning as described.

Hinge means H comprises in the preferred form, a downwardly-dependant arm 14 of metal or similar material. A hinge 15 having a hinge pin 15a is secured to the upper end of arm 14 and also to the under surface of bar 10. The upper end of arm 14, in this instance, is of a length sufficient to contact bar 10 when the arm 14 is vertical as indicated by reference to number 16. Thus arm 14 will be allowed to swing inwardly toward the structure S but will be limited against outward swinging when the portion 16 abuts the under surface of bar 10. This is true at all times and at all positions of the bar 10. The arm 14 being limited to an outward position of 90 degrees from the axis of the support members 11 by the abutment 16.

The lower portion of arm 14 has in this in-

stance, an elongated aperture 17. A tubular member is made to slide freely in the aperture 17, and is slightly longer than the thickness of the arm 14. A bolt 19 is provided with a washer 20 which is then passed through a hole in the valance V. Tubular member 18 is then placed upon the bolt 19. After the tubular member 18 is passed through the aperture 17 a washer 21 and a nut 22 completes the assembly. Washer 21 prevents the tubular member from disengagement from aperture 17. Thus it is clear that the valance V will be clamped between the washer 20 and the tubular member 18 and will be also anchored to the arm 14. The valance V will have freedom to creep relative to the aperture 17 when the arm 14 swings inwardly toward the structure S. Thus the valance V is allowed to hang freely but is prevented from being blown up over the roof R of the awning, by the washer 21 which in turn is held against outward movement by the arm 14, the latter being restrained by contact of portion 16 abutting bar 10.

Figs. 6 and 7 show the modification which will now be explained: In this instance arm 23, which is similar to arm 14 above, has a hole 24 which accommodates a bolt 25. The valance V has inserted therein an elongated grommet 26 of the type usually used with fabric for the purpose of strengthening. Abutting the arm 23 in this instance is a tubular member 27 which is of sufficient length to avoid restricting relative creeping of the valance V, and is of a diameter so as to freely slide in the grommet 26. The bolt 25 having a washer 28, is passed through the tubular member 27 and then through the arm 23. A washer 29 and a nut 30 complete the assembly of the modification.

It will be observed that as the awning is raised to the position where the roof R is completely rolled up on the drum D, the valance V will never be allowed to move outwardly more than 90 degrees from the support member 11. It is clear then, that by the use of this invention the valance V can never be blown up over the roof R of the awning regardless of the position of the latter.

The modification shown in Fig. 8 comprises a tubular bar 31 which forms the front portion of the frame F and which replaces the bar 10, above. Secured to the bar 31 by drive screws 32 or other suitable means, is a hinge 33. One butt of hinge 33 is formed to fit the contour of the bar 31. The other butt of the hinge 33 is directed downwardly. Secured to the above-mentioned downwardly directed portion of hinge 33 is an arm 34. This arm 34 is similar to the arm 14 mentioned above, the function of both being identical. The upper portion 35 of arm 34 abuts the bar 31, so as to prevent outward swinging of the arm 34. The fastening of the awning to the bar 31 is similar to that employed when the conventional wood bar 10 is used.

The above being a complete description of an illustrative embodiment of the invention, what is claimed as new and desired to be secured by Letters Patent of the United States is:

1. In an awning having a front bar and a downwardly extending valance fixed thereto, in combination, means to prevent the outward swinging of the said valance when the said awning is in the extreme downward position, comprising a first hinge member secured to the lower face of the said front bar adjacent the front vertical face thereof, a downwardly extending second hinge member disposed adjacent the said

valance, a hinge pin pivotally connecting the said first and second hinge members, said second hinge member being provided with an abutment at the extreme upper end thereof for engagement with the lower face of the said front bar to prevent the said second hinge member from outward swinging beyond the vertical position when the said awning is in the extreme downward position, said second hinge member being provided with a longitudinal aperture at the lower end thereof, a tubular member loosely connected to said aperture, the length of said tubular member being in excess of the thickness of the said second hinge member, fastening means securing the said tubular member to the said valance and means confining said tubular member to a sliding engagement relative to the said aperture.

2. In an awning having a frame and a downwardly directed valance, in combination, means to prevent the outward swinging of the said valance when the said awning is in the extreme operative position, comprising a first hinge member secured to the said frame, a downwardly extending second hinge member, pivotal means connecting the said first and second hinge members, said second hinge member being provided with an abutment for engagement with the said frame to prevent outward swinging of the said second hinge member when the said awning is in the extreme operative position, said second hinge member having an aperture at the lower extremity thereof, a guide member adapted to slide freely in the said aperture, means for securing the said guide member to the said valance, said guide member being freely movable in said aperture and means to maintain the said guide member in sliding engagement within and with the said aperture.

3. In an awning secured to a structure and having a frame and a downwardly depending valance, in combination, a downwardly depending member to prevent the said valance from swinging outwardly from the said structure when the said awning is in the operative position, comprising a first hinge member secured to the said frame, a second and downwardly depending hinge member pivotally associated with the said first hinge member, said second hinge member being provided with an abutment to prevent outward swinging of the said second hinge member but allowing inward swinging thereof toward the said structure, said second hinge member having an aperture substantially near the lower end thereof, a guide member adapted to slide freely in the said aperture and means for securing said guide member to the said valance, said guide member being of a length freely slidable within and along the said aperture.

4. In an awning having a frame and a downwardly directed valance attached thereto, in combination, a first hinge member secured to the said frame, a second hinge member pivotally depending from the said first hinge member and adjacent the said valance, said second hinge member being provided with an abutment for engagement with the said frame to limit the said second hinge member to inward swinging from the vertical when the said awning is in the said normally downwardly extending position, said second hinge member having an aperture in the plane thereof substantially near the extremity and means associated with the said valance having slidable engagement with the said aperture.

5. In an awning having and provided with a valance secured thereto and provided with a

front bar, in combination a first hinge member secured to the said front bar, a second hinge member pivotally depending from the said first hinge member and adjacent the said valance, said hinge members having abutting means to prevent the said second hinge member from assuming an angle in excess of the vertical outwardly when the said awning is in the downwardly extending position, said second hinge member being provided with an aperture, a guide member adapted for sliding engagement relative to the said aperture, the length of the said guide member being slightly in excess of the thickness of the said hinge member, fastening means to secure the said guide member to the said valance and means to prevent disengagement of the said guide member from the said aperture.

6. In combination with an awning having a front bar and a depending valance, a first hinge member secured to the said bar, a second hinge member pivotally depending from the said first hinge member, and adjacent the said valance, means associated with the said second hinge member to prevent outward swinging thereof, said second hinge member being provided with an aperture at the lower extremity thereof, anchor means secured to the said valance freely engaging said aperture to retain the relative association between the said valance and the said second hinge member.

7. In combination with an awning secured to a structure and having a frame and a depending valance, a depending pivoted member adjacent the said valance and secured to the said frame, abutment means associated with the said pivoted member to prevent the latter from pivotal movement away from the said structure in excess of the depending position of the said pivoted member when the said awning is in the normally operative position, said pivoted member having an aperture in the plane thereof spaced from the said frame, an anchor means freely connected to said aperture and secured thereto against disengagement therefrom and means to secure the said anchor means to the said valance.

8. In combination with an awning secured to a structure and having a frame and a depending valance, a depending member pivoted to the said frame adjacent to the said valance, means to prevent the said depending member from pivotal movement away from the said structure substantially in excess of the depending position of the said depending member when the said awning is in the normally operative position, said valance having an aperture spaced from the said frame, anchor means freely connected to said aperture and secured against disengagement therefrom and means to secure the said anchor means to the said depending member.

9. In combination with an awning secured to a structure and having a depending valance, a pivoted member adjacent to the said valance, means associated with the said pivoted member to prevent the latter from pivotal movement away from the said structure substantially in excess of the depending position of the said pivoted member when the said awning is in the normally operative position, said pivoted member having an aperture, an anchor means freely connected to

said aperture and secured against disengagement therefrom and means to secure the said anchor means to the said valance.

10. In combination with an awning secured to a structure and having a depending valance, a pivoted member adjacent to the said valance, means associated with the said pivoted member to prevent the latter from pivotal movement away from the said structure substantially in excess of the depending position of the said pivoted member when the said awning is in the normally operative position, said valance having an aperture, an anchor means freely connected to the said aperture and secured against disengagement therefrom and means to secure the said anchor means to the said pivoted member.

11. In an awning having a frame and a depending valance, in combination, a hinged member depending from said frame and adjacent said valance, said valance provided with an aperture, anchor means secured to said pivoted member and confined to movement in said aperture.

12. In an awning having a depending valance, in combination, a hinged flat depending member adjacent said valance and having a guide slot in the face thereof, anchor means intermediate said valance and said depending member, one end of said anchor member secured to said valance and the other end thereof freely slideable in said guide slot.

13. In an awning having a depending valance, in combination, a pivoted depending member adjacent said valance and having a guide slot in the surface thereof, an anchor member intermediate said valance and said depending member, one end of said anchor member secured to said valance and the other end thereof slidably engaged in said guide slot.

14. In an awning having a depending valance, in combination, a depending member having a slot and positioned adjacent said valance, an anchor member intermediate said valance and said depending member, one end of said anchor member secured to said valance and the other end loosely confined in said slot.

15. In an awning having a depending valance, in combination, a depending member adjacent said valance and having a vertical guide aperture, an anchor member intermediate said valance and said depending member, one end of said anchor member secured to said valance and the other end loosely engaged in said guide aperture and confined to vertical movement therein.

16. In an awning having a depending valance provided with an aperture, in combination, a hinged depending member adjacent said valance, anchor means intermediate said valance and said depending member, one end of said anchor means secured to said depending member and the other end thereof confined to a slideable engagement in said aperture.
